Inventor:

Orville M. Knox,

UNITED STATES PATENT OFFICE.

ORVILLE M. KNOX, OF ONEIDA, NEW YORK.

DRYING-FLOOR FOR HOP-HOUSES.

SPECIFICATION forming part of Letters Patent No. 281,273, dated July 17, 1883.

Application filed January 15, 1883. (Model.)

To all whom it may concern:

Be it known that I, ORVILLE M. KNOX, a citizen of the United States, residing at Oneida, in the county of Madison and State of New York, have invented a new and useful Improvement in the Drying-Floors for Hop-Houses, of which the following is a specification.

My invention relates to improvements in drying-floors for hop-houses, in which certain slats are laid edgewise upon a plate of wood or metal between upright supports from said plate, said plate resting upon joist and fastened thereto, said slats being secured in position by a plate-holder and screws, and so arranged as to permit a greater volume of heated air to pass up from the heated room beneath, through said slats to the hops arranged therein for drying.

20 The object of my improvement is to afford greater facilities for drying hops; to save time and labor in drying them by improving the condition of the hops, when dried, by drying them with greater uniformity; to dry larger 25 quantities of hops at the same time and within the same space, and to generally facilitate the process of drying hops. I attain these objects by the mechanism and combination illustrated in the accompanying drawings, in 30 which—

Figure 1 represents a section of base-plate B, with upright supports C C, and spaces intervening to receive the slats A A. Fig. 2 represents a detached view of the relative position of base-plate B, the slats A A, plate-holder H, screw and holes I J K, and joist G. Fig. 3 represents the floor complete, excepting the covering of thin fibrous material to prevent the hops from sifting through the 40 floor. Fig. 4 represents a section of said floor.

Similar letters refer to similar parts throughout the several views.

G is the joist and support of the floor.

B is the base-plate supported by joist G.

45 C C are the upright supports from and form a permanent part of base-plate B, with intervening spaces.

A A are the slats, which are inserted edge-

wise between the supports C C, and form the upper surface of said floors.

50

H is a plate-holder used to secure the slats in position.

K K are screw-holes running through and securing plate-holder H, supports C C, and base-plate B to joist G. I are screws to secure 55 the same, all as hereinafter set forth.

I attain the construction of the floor as follows: Joist G constitutes the ground-work of the floor, and is a part of the building. Upon joist G, I place base-plate B, which is an iron, metallic, or wood plate made in sections, of convenient size and length, and is placed upon joist G of the building. It is fastened to and supported by joist G by means of screws through the plate, or by pins or staples over projections from the sides. It is provided with upright supports C C. If a casting of metallic substance, they form one piece; if of wood, the supports C C are set into slots or grooves in the upper face of plate B, and are made 60 permanent by means of pinning, gluing, or screws. The slats A A are put into the spaces between the supports edgewise until the floor is laid. They are of wood, and of convenient length, width, and thickness. They are secured at the ends thereof, and when necessary, after being placed in position, by plate-holder H H. This plate-holder is of sufficient size, length, thickness, and strength. I lay it over and fasten it upon the supports C C whenever 65 needed for securing the slats A A in position. It is set into slots or grooves in the slats of equal depth with the thickness of the plate-holder H, and fastened down by means of screws I. Screw I is put through plate-holder 70 H, supports C C, and base-plate B, into joist G, making thus secure and permanent the entire floor, as represented by Fig. 3. This floor is covered by a thin cloth or fibrous material, over which are spread the hops for drying. 75

I claim as my invention and I desire to secure by Letters Patent—

1. In a hop-drying floor for hop-houses, the combination, in the floor, of joist G, base-plate B, with upright supports C C, with slats A A, 80 and plate-holder H, with screw I and screw-

90

95

holes J K, put together, each adapted to the other and permanently constructed, as herein described.

2. In a hop-drying floor, the combination 5 of the slats A A, the base-plate B, resting upon and supported by joist G, fastened as aforesaid, provided with upright supports C C, the slats A A, C C, put in edgewise between the supports and plate-holder H, fastened over and upon the supports C C, set into slots or grooves in

the top of slats A A, at the ends of the slats, and wherever required to make the floor firm and to secure the slats in position, as and for the purposes substantially as above set forth.

ORVILLE M. KNOX.
